UNITED STATES PATENT OFFICE.

EDGAR M. BIRDSALL, OF BUFFALO, NEW YORK, ASSIGNOR TO MARY BIRDSALL, OF SAME PLACE.

STEAM-ENGINE.

SPECIFICATION forming part of Letters Patent No. 415,438, dated November 19, 1889.

Application filed December 26, 1888. Serial No. 294,598. (No model.)

To all whom it may concern:

Be it known that I, EDGAR M. BIRDSALL, of the city of Buffalo, in the county of Erie and State of New York, have invented new and useful Improvements in Steam-Engines, of which the following is a specification.

This invention relates to the cross-heads and connecting-rods of steam-engines, and has the object to provide simple and convenient means whereby the wear-plates of the cross-head may be adjusted for wear.

My invention consists of the improvements which will be hereinafter fully described, and pointed out in the claims.

In the accompanying drawings, Figure 1 is a side elevation of a horizontal engine provided with my improvements. Fig. 2 is a vertical longitudinal section of the cross-head and the adjacent end of the connecting-rod on an enlarged scale. Fig. 3 is a transverse section in line $x-x$, Fig. 2. Fig. 4 is a horizontal section in line $y-y$, Fig. 2. Fig. 5 is a vertical section in line $z-z$, Fig. 3, looking toward the right.

Like letters of reference refer to like parts in the several figures.

A represents the steam-cylinder, a the piston-rod, and B the frame or extension of the steam-cylinder, in which are formed the longitudinal guides b .

C represents the cross-head, to the front end of which the piston-rod a is attached, and D is the connecting-rod attached at its front end to a stud or journal d , formed on one side of the cross-head, and at its opposite end to the wrist-pin of the crank-wheel d' .

E E' represent the wear-plates of the cross-head, which run in contact with the guides b . The inner sides of these wear-plates are inclined, as shown at e in Fig. 2, and the contiguous faces e' of the cross-head are correspondingly inclined, so as to form with the straight faces of the guides b tapering spaces in which are arranged the wear-plates E E'. The inclined faces of the cross-head are so arranged that the spaces between the same and the guides b contract in opposite directions, so that the wear-plates will be moved in opposite directions in adjusting the same. The wear-plates are held against displace-

ment upon the cross-head by means of lips or flanges f , extending lengthwise along the edges of the plates and overlapping the sides of the cross-head, as shown in Figs. 2 and 3.

G represents a segmental shifting-plate 55 turning upon the outer end of the journal d of the cross-head, the shifting-plate being provided with a circular depression or socket g , which fits over said journal. The shifting-plate G is attached to the adjacent side of 60 the cross-head by clamping-bolts h , passing through curved slots h' , formed near the peripheral edge of the shifting-plate.

i represents laterally-projecting studs or pins formed on or secured to the outer sides 65 of the wear-plates E E and engaging in recesses or depressions j , formed in opposite sides of the shifting-plate G, so that by turning the plate G the wear-plates E E will be simultaneously shifted in opposite directions 70 by means of the studs i .

The shifting-plate G is provided with a square projection g' , to which a wrench may be applied for turning the plate. Upon loosening the clamping-bolts h the shifting-plate 75 can be turned so as to move the wedge-shaped wear-plates farther into the tapering spaces between the cross-head and the guides b to take up any wear of the plates. After the wear-plates have been properly adjusted they 80 are firmly held upon the cross-head by tightening the clamping-bolts h , the studs i holding the wear-plates against longitudinal movement on the cross-head by being seated in the recesses j . Both wear-plates are in this 85 manner adjusted uniformly and evenly, thereby maintaining the cross-head in line with the piston-rod at all times and preventing binding of the parts.

The connecting-rod D is provided at or near 90 its end with an elongated opening or recess k , which is curved at its outer end, as shown at k' , to form a concave seat for one of the brasses or sections l of the bushing which surrounds the journal d of the cross-head. 95

m represents a follower or movable block arranged in the recess k and provided with a concave seat m' , which bears against the other section l' of the bushing.

n is an adjusting-screw whereby the fol- 100

lower *m* is moved toward the journal *d*, and which engages with its threaded front portion in a threaded opening *n'*, formed in the rear side of the follower *m*. The adjusting-screw *n* is provided with a nut or collar *o* for turning the same, which bears against the inner wall of the recess *l*, and whereby the screw is held against lengthwise movement. The inner rear portion of the adjusting-screw *n* is preferably made smooth and fits in an opening or socket *o'* in the adjacent portion of the connecting-rod.

p is a jam-nut arranged on the adjusting-screw *n* and bearing against the rear end of the follower *m*, so as to clamp the screw in position after being adjusted.

*o*² represents a stud formed on the bushing *l* and seated in an opening in the concave face of the connecting-rod *D*, whereby the brasses *l l'* are held against turning.

When the brasses *l l'* become worn, they are moved against the journal *d* to take up the wear by turning the adjusting-screw *n* so as to move the follower *m* toward the journal.

The nut or collar *o* may be provided with a series of openings, as shown, into which a bar is inserted for turning the adjusting-screw.

By this construction the connecting-rod, with its recessed end portions, can be cast in one piece of steel or other suitable metal,

which renders the rod strong and light. The usual projecting keys and gibbs are dispensed with and a simple and reliable adjusting device substituted, which is especially desirable for the connecting-rods of traction-engines.

I claim as my invention—

1. The combination, with the cross-head provided with inclined faces, of adjustable wear-plates having inclined inner sides resting against the inclined faces of the cross-head and provided with studs or pins, and a shifting-plate attached to the cross-head and provided with recesses or depressions in which said studs engage, substantially as set forth. 40

2. The combination, with the cross-head provided with inclined faces, of adjustable wear-plates having inclined inner sides resting against the inclined faces of the cross-head and provided with studs or pins, a shifting-plate provided with recesses or depressions in which said studs engage and with curved slots, and clamping-bolts passing through said slots and whereby the shifting-plate is secured to the cross-head, substantially as set forth. 50

Witness my hand this 21st day of September, 1888.

EDGAR M. BIRDSALL.
